UNITED STATES PATENT OFFICE.

SARAH A. ALBERTSON, OF DE FUNIAK SPRINGS, FLORIDA, ASSIGNOR OF
ONE-THIRD TO JONATHAN A. JORDAN, OF HOT SPRINGS, ARKANSAS.

WASHING-MACHINE.

SPECIFICATION forming part of Letters Patent No. 631,357, dated August 22, 1899.

Application filed March 30, 1899. Serial No. 711,123. (No model.)

To all whom it may concern:

Be it known that I, SARAH A. ALBERTSON, a citizen of the United States, residing at De Funiak Springs, in the county of Walton and 55 State of Florida, have invented certain new and useful Improvements in Washing-Machines, of which the following is a specification.

This invention has relation to improvements in washing-machines; and it consists in the novel construction, combination, and arrangement of parts, all as will be hereinafter fully explained, and particularly pointed out in the claims.

15 The annexed drawings, to which reference is had, fully illustrate my invention, in which—

Figure 1 represents an end view of my device. Fig. 2 is a vertical transverse sectional view of the same. Fig. 3 is a side view. Fig. 20 4 is a plan view of the vertically-sliding bracket, and Fig. 5 is an inverted plan view of one of the clamps.

Referring by letter to the accompanying drawings, A designates the washing-machine, 25 of which a a are the end uprights, which are connected to one another by the horizontal bar b, forming the frame of the machine. The end pieces a a are provided with openings c c, in the bottom of which is journaled 30 the shaft d, carrying the revolving brush e, and which is held down in position by the spring f, which is interposed between the block g on the journal d and the block h in the slot c. A thumb-screw α^2 , passing through 35 a female screw-threaded plate g, serves to regulate the pressure of said spring upon the journal. At each end of the frame is secured a vertical bar n, upon which slide brackets o, having upper and lower lugs p p, through 40 which said bar passes, and near the top thereof the same is provided with a short arm r, extending at right angles to the bracket and resting upon the journals d d, while the end s is bent upon itself, providing a lug t, having 45 a perforation to receive the end journals of the pivoted board t, which, in connection with the pivoted board x, forms a shield, said board being pivoted at w to the top of the frame and the lower free end resting upon the upper 50 end of the pivoted board t, as at y.

Within the frame are corrugated rollers m m and l l, the former being somewhat larger than the latter, and each has its ends bearing in the end pieces of the frame, and in connection with these rollers I employ a longitudinally-corrugated bar j, which is interposed between the two smaller rollers, and the same, as well as said rollers, engage the revolving brush.

z represents clamps which are bent at their 60 upper ends for grasping the upper edge of an ordinary washing-tub, and the same is held firmly thereto by the thumb-screws a. The lower portion of each of these brackets or clamps is bent into a horizontal plate c', having a slot c² to receive the thumb-screws c³, by which the clamp is held to the bar b and made laterally adjustable thereon.

It will thus be observed from the above description, when taken in connection with 70 the annexed drawings, that after the device is set water is placed in the washing-tub and the clamps are adjusted and secured in place thereon, the handle b' is turned, and the clothing to be washed is passed between the brush 75 and rollers and fluted bar. At the same time the shield or pivoted boards t and x prevent any water from splashing beyond the tub.

When it is desired to raise the shield, the two sections or boards forming the same are 80 simultaneously raised simply by the operator raising the shaft d, causing the short arms r to rise and carry with them the brackets, the same sliding vertically on the rods n, which raise the vertical board t, and the latter in 85 turn raising the free end of the slanting board, causing it to turn on its pivot, or, if desired, the operator can raise the brackets without raising the shaft d by grasping the short arms r at each end of the machine and 90 forcing them upward, thus raising the brackets and the vertical and slanting board.

In Fig. 3 the common coiled spring is shown engaging at one end the board b and at the other end the journal of the brush, to 95 which construction I lay no claim.

Having thus described my invention, what I claim, and desire to secure by Letters Patent, is—

1. The combination with the brush-roller 100

and fluted rollers all journaled in the frame and the fixed fluted bar, of the shield comprising the two sections t , and x ; the section t , pivoted to the frame and the section x , pivoted to the sliding brackets, the whole adapted to operate, substantially as described.

2. The combination with the frame, brush-
roller, fluted rollers and fixed fluted bar; of
the upper and lower pivoted sections forming
10 a shield, the sliding bracket, provided with

the short arm r , perforated lugs p , p , and the bent end s , the end or lugs t' , having perforations to receive the journals of the board t , all substantially as described.

In testimony whereof I have affixed my signature in presence of two witnesses.

SARAH A. ALBERTSON.
